PUSH-BUTTON OPERATED PERMUTATION
LOCK

Antonio Soler Capdevila, Barcelona, Spain

Application April 14, 1947, Serial No. 741,388

In Spain April 17, 1946

3 Claims. (Cl. 70—299)

1

This invention relates to the construction of locks for strong boxes and safes, and its object is a lock mechanism intended to establish a secret or combination that is actuated by a series of buttons or feelers arranged in such a manner that on some of the said feelers being pressed a number of times determined on, the combination that will permit the movement of the locking arms or bolts of the door of the safe is set up.

A further object of this invention is the arrangement of the means that permit the secret or combination to be changed at will, for the purpose of being able to change it with ease whenever this may be found suitable, offering the advantage that the combination may be brought about by two or more persons conjointly, without it being necessary for each of them to know the secret or combination of the other, and the mechanism only operating when the conjunction or the whole of the two or more partial combinations has been carried out.

The lock mechanism constructed in accordance with this invention has, as its principal components, a certain number of feelers or buttons supported and guided by a piece in the shape of a plate or disc that is attached to the front wall of the safe, in combination with a second plate that supports a series of plungers capable of axial displacement in correspondence to or in response to the feelers, the said plungers constituting the locking members, in such a manner that it is necessary to displace axially each one of them a previously determined magnitude, which, moreover, may be different for each of them so that on obtaining a predetermined position of all or several plungers, the lock opens displacing a stop peg that limits or leaves free the movement of the bolts of the safe.

The feelers slightly project beyond the surface 40 of the outside wall of the safe, and each one of them is marked with letters, numbers or other signs that enable them to be differentiated, so that they may be pressed inwards, each of the required feelers in turn and a variable number of times, in accordance with the previously determined combination or secret established.

Each one of the feelers is provided with a locking tooth or cog that catches in the teeth of a cogged rack arranged on a cylindrical 50 plunger placed parallel to the feeler in such a manner that every time the feeler is pressed it brings the plunger forward to the extent of one tooth or cog. The plunger bears a pin that projects beyond the plate that supports the feel-

ers, and this pin, in its turn, knocks against other pins corresponding to it and lodged in a rear supporting plate that is provided with a concentric gyratory disc having a series of locking teeth whose position may be varied, in combination with a groove made in the body of the said pins, so that when these pins are displaced and the grooves of each one of them comes onto the plane assigned to it in accordance with the 10 previously carried out combination, the said grooves are then opposite the corresponding teeth or cogs of the movable plate or disc, and the said plate is able to rotate to a certain extent, thus bringing about the displacement of the bolts or locks, which are thus left free and may be operated by means of an independent handle on the outside.

In the attached drawings there is represented, as an example, a construction of the lock mechanism that is the object of this invention.

Figure 1 is a view of the mechanism from the outside or from in front of the door of the safe.

Figure 2 is a front view of the mechanism along the line II—II of Figure 4, that is to say, 15 behind the frontal plaque of the feelers.

Figure 3 is a partial section along the line III—III of Figure 2, showing the whole block of the organisms operated by each feeler.

Figure 4 is a longitudinal section of the whole, along the plane of the locking pins, in accordance with the line IV—IV in Figure 2.

Figure 5 is a transversal section along the line V—V in Figure 4, and shows the plate that carries the locking teeth.

Figure 6 shows the organisms that bring about the displacement of the stop pin when the plate represented in Figure 5, revolves, and is a section along the line VI—VI of Figure 4.

Figure 7 is a detail showing the variable fixing of the locking teeth, which enables the secret to be varied and adjusted at will.

Figure 8 is a cross-sectional view taken on the line VIII—VIII of Figure 4.

The lock mechanism object of this invention comprises a frontal plaque 10 having several feelers 11 distributed in a circle and each one of which is constituted by a button 11' as in Figure 3, attached to a cylindrical pin 12 that lodges in suitable cavities made in the double plate 13—14 (Figure 4) and situated behind the feeler plate. The plate 13—14 is double, and one of the pieces of which it is composed 14 has a hollow collar 15 in its center that serves as a bearing for the axle 16 that passes through the frontal plaque 10 and finishes on the outside in

the handle 17. The other piece 13 fits into 14 forming practically a single piece and both pieces are coupled together by means of reciprocal indentations, bolts, pins, or similar means. In the center of this plate 13 is the gyratory piece 18 which rests on the outside surfaces of the collar 15, and the object of which will be explained later on.

The double plate 13—14 is provided, on its outer edge, with a series of cylindrical cavities 20 as in Figure 3, in which are lodged the pins 12 of the feelers, which are capable of axial displacement in the said cavities and are guided inside the cylindrical cavity in which they are lodged by the projection 21 that is introduced into a suitable slot or groove in the cavity, the pin being continuously pushed outwards by the spring 22. Parallel to the cavity 20 for the feeler there is another cylindrical cavity 23 in which there is lodged a pin or plunger 24 which can also be displaced axially and is provided with a slot 25 in cooperation with pins 25' (Fig. 2) to guide its axial displacement and is, moreover, of a solid piece with a stem 26 that projects on the outer part of the plate.

The pin 12 of the feelers is split and has inside it, a tooth or pawl 27 that, by the action of a small spring 10, tends to jut out sideways through an opening or window 28 that connects the two cylindrical cavities, the tooth 27 catching in one of the cogs of the toothed rack 29 made on the side of the plunger 24, the said plunger being pushed outwards by the spring 30. The lower part of the plunger 24 also has a series of teeth or cogs, or a ratchet 31, as in Figure 4, in which a trigger or lock-bolt 32 will catch, which trigger is radially displaced in a cavity made for this purpose between the faces of contact of the two half plates 13—14, when the said trigger is pushed against the plunger by the spring 33.

In this manner, every time that the feeler is pushed inwards, the plunger 24 is brought forward to the extent of one cog or tooth and, as soon as the said plunger has reached its new position it is held there, without any possibility of its going back, by the trigger or lock-bolt 32, so that the stem or rod 26 will remain displaced towards the back to an extent corresponding to one tooth.

In a line with the stems or rods 26 there are the rods or pins 35 attached to the plungers 36 that are lodged in corresponding cavities 37 made in a circular plate 38 in the rear plate of the mechanism and pushed towards the front by springs 31'. This plate is fixedly mounted at the end of the principal axle 16 and, concentric with it there will be found, in front of plate 38, a second plate 39 that can revolve and that carries a series of collar guides 40 parallel to the axle (Figures 4 and 5), split lengthwise, and in which there can slide in an axial direction a piece 41 that constitutes the stop tooth or cog, suitably guided in the collar 40 and projects on the outside through the above-mentioned split, having an appendix in the shape of a tongue 42 bent in the direction of a transverse plane with respect to the axis; the plate 39 which carries the series of collars 40 can be rotated with a limited angle. This piece 41 is able, as has already been stated, to slide axially in the hollow collar that serves as a guide for it, but its position can also be fixed at any desired or suitable point, and, for this purpose the lower edge of this runner or slide piece 41 is provided with a series of teeth or indented ratchet 43, and at the bottom or base of the col-

lar there is a transversal split 44. Concentric with the plate 39 and revolving on its central cube or collar 45 there is the disc 46 having on its outer edge a series of leaves or claws 47 that extend beyond the edge of the disc and are so arranged that when this disc is rotated in a certain direction they will become engaged in the slots 44 and catch in one of the teeth of the runner or slide 41 thus fixing its position more or less introduced into the collar that serves it as a guide.

On the other hand the plunger 36 of the pin 35 is guided in its axial movement inside the cavity 37 by the claw 48 that is introduced into the slot 49 of the said cavity. The said plunger 36 has, on its lower part or edge a transverse groove or slit 50 so arranged that when all the grooves are opposite the tongues 42 of the pieces 41 that are fixed at a certain height in the collars, these tongues 42 may be introduced into the grooves 50, by the rotation of the disc or plate 39. The plate 39 bears on its rear face the pin or projection 51 the end of which is introduced into the slot 52 (Fig. 6) of the slidable plate 53 situated in the inside cavity of the supporting plate 38. This slidable plate 53 is so arranged that it may be displaced vertically, and is guided by the axle-case 54 itself of the plate 38 and by a guide screw 55 that is introduced into suitable slots in said slidable plate. The plate 39 rotates, driven by the proper weight of the slidable plate 53, when all the grooves 50 are in front of the tongues 42. The movement of this slidable plate and plate 39 can also be obtained through a spring, the slidable plate displacing in any convenient direction. The return of the plungers 36 to their position of departure is obtained by causing the handle 17 to rotate towards the left, whereby the tooth 39' provided in the axle 16, drives the plate 39 also towards the left, disengaging the tongues 42 from the grooves 50, the plungers remaining free and moving forward through the springs 37'. The slidable plate has a stem or rod 56 that extends to the outside, and its end constitutes a stop pin combined with the bolts or latches of the door, in such a manner that when it is in a position that has been fixed or determined on, it prevents the displacement of these bolts or latches, which are worked independently by means of an external hand-wheel.

The combination is established by pushing a selected number of feelers (or all the feelers) one or more times each. The plungers, after the displacement caused by each pushing, are retained by the triggers 32.

The plate 18 mentioned at the beginning is for the purpose of causing the plungers and the pins or pegs to return to their first or original position at starting. For this purpose the plate 18, as may be seen in Figure 2, is provided with a series of openings 57 at its outer edge that form a tooth with a sloping profile 58 and on the other hand the triggers or lock-bolts 32 are provided with a small peg or taper pin 59 that projects through the said opening and lies against the sloping edge of the respective tooth.

When it is desired to annul the combination, the disc 18 is rotated through a small angle from the outside by means of the handle 17 and through the intervention of a displaceable stem 60 worked by the lateral press-button 60'; the end of said stem 60 protrudes and is introduced in the bore 60'' of the disc 18, whereby, upon the handle 17 rotating to the right, a slight rotation is given said disc 18, acting on the pins 59 and causing the radial displacement of all the triggers 32,

leaving free the plungers previously displaced, which return to their original position through the action of their respective springs 30.

As has already been said, the runner or slide pieces 41 that move inside the tubular collars 40 have a series of teeth of their lower edge. This permits the setting up of whatever secret code or combination may be desired by fixing these slide pieces at a greater or lesser distance inside with respect to their collars, whereby the position of the lock-tooth 42 will also be changed, and the corresponding pin will have to be pressed or brought into action a greater or lesser number of times, according to the position of the slide piece referred to. This arrangement will enable the combination or secret code to be changed with the greatest facility when so desired, it being sufficient for this purpose to introduce a key into the back part through the opening 61, by means of which the disc or plate 46 shown in Figure 5, that carries the peripheral indentations 47, is caused to turn through a slight angle, the slide pieces 41 being left free within their guide but all of them joined to the corresponding plunger by the tongue 42, after which all the plungers are returned to their initial position training the slide pieces 41, and, then by means of the feelers, the new combination that may be desired is established, whereby the pieces 41 will take up a position other than the original one and will be locked or fixed by the disc 46 returning to its position on the above-mentioned key being withdrawn.

The mechanism described permits the secret or combination to be changed at will whenever this may be found suitable and affords the advantage that the combination can be formed conjointly by two or more persons, without it being necessary for each of them to know the secret or combination of the others, and the mechanism only operates when the whole or conjunction of the two or more partial combinations has been carried out.

I claim:

1. A push button operated permutation lock comprising in combination a central axle member and an external handle therefor, a front supporting plate adapted for attachment to the front side of a door, a plurality of feelers arranged in a circle on said front supporting plate, a two piece plate mounted behind said front supporting plate and having a plurality of cylindrical cavities therein in alignment with said feelers, slideable pins in said cavities joined to said feelers, a pawl pivotally mounted in each said pin, spring means urging said pawls outwardly from said pins, spring means urging said pins outwardly toward the front of a door, said plate having a plurality of cylindrical cavities therein parallel to said first said cavities and of equal number therewith, plungers slidably mounted in said second said cavities and being spring biased forwardly, toothed racks on a side of said plungers for coaction with said pawl, a stem connected to each

said plunger extending rearwardly, a rear plate having cylindrical cavities therein mounted on said axle member and adapted for attachment to the rear side of a door, a plurality of axially displaceable pins supported at one end thereof in said cavities in said rear plate and corresponding in number to said feelers, the ends of said pins being in line with said stems extending rearwardly from plungers and in proximity thereto, a rotatable disc on said central axle in proximity to said rear plate, slideable members mounted around the periphery of said rotatable disc and each having a tooth thereon, each said pin having a transverse slot therein, said pins being differentially and selectively displaceable axially by actuation of said feelers for aligning said slots and said teeth, a sliding plate carrying a bolt stop pin thereon operatively connected to said rotatable disc, whereby upon alignment of all said slots and all said teeth said disc may be rotated by said central axle for actuating said sliding plate displacing said bolt stop pin.

2. In a lock mechanism as claimed in claim 1, said plungers having a second toothed rack radially disposed with respect to said central axle, a plurality of trigger members slidably disposed in said plate behind said front plate spring pressed toward said second toothed rack for coaction therewith, a rotatable plate in close proximity to said trigger members having a plurality of openings therein and forming a series of inclined teeth, taper pins for each said trigger and extending through said openings and contacting said inclined teeth, and means for rotating said plate having said trigger members for displacing all said triggers toward said central axle through said taper pins and said inclined teeth whereby said plungers and said pins are free to return to their original position under the action of their respective said springs.

3. In a lock mechanism as claimed in claim 1, said slideable members mounted around the periphery of said rotatable disc having a plurality of teeth on the underside thereof, a second rotatable disc concentric with said first said rotatable disc on said axle, a plurality of claw members on the periphery of said second rotatable disc for engagement with said teeth on said slideable members, said claw members and said teeth coacting to fix said slideable members in a predetermined position.

ANTONIO SOLER CAPDEVILA.
